COMPRESSOR

Julius Naab, Easton, Pa., assignor to Ingersoll-Rand Company, New York, N. Y., a corporation of New Jersey

Application June 23, 1948, Serial No. 34,712

3 Claims. (Cl. 230—22)

1

This invention relates to compressors, and more particularly to unloaders for multi-stage compressors.

One object of my invention is to completely unload a multi-stage compressor in a relatively simple and automatic manner.

Other objects will be in part obvious and in part pointed out hereinafter.

In the drawings accompanying this specification and in which similar reference numerals refer to similar parts,

Figure 1 is an end view, partly in section, of a two-stage compressor embodying the present invention,

Figure 2 is a transverse view taken through Figure 1 along the line 2—2,

Figure 3 is a transverse view taken through Figure 2 along the line 3—3 and shows the construction of a valve means for controlling communication between the inlet and clearance pockets of the second stage compressor, and

Figure 4 is a view through Figure 1 along the line 4—4 and shows the by-pass valve arrangement for the low pressure stage.

Referring to the drawing, number 10 designates, in general, a two-stage variable capacity compressor provided with clearance valves 11 and 111 that control the output, or capacity, of the low pressure stage 15 and high pressure stage 16, respectively. The valves 11 and 111, are actuated by pressure fluid supplied thereto through conduits 212 and 312, respectively, connected to a conventional regulator 12. The regulator 12, in turn, is supplied pressure fluid from a source, such as a receiver (not shown) for the compressor discharge, and is connected by a conduit 112 to a point (not shown) in the fluid system and is responsive to variations in pressure at such point to control the compressor output in a conventional manner. Further control over the unloading of the compressor is provided by means of by-pass valves 13 and 14 adapted respectively to the low and high pressure stages 15 and 16 of the compressor. The valves 13 and 14 cooperate in such a manner that pressure fluid in the high pressure stage may be by-passed through an intercooler 17, connected in series between the two stages—that is, between the outlet of one cylinder and the inlet of the preceding cylinder, and thence through the low pressure stage 15 to the inlet or suction side thereof.

As shown, the compressor 10 is of the double acting type and accordingly each stage 15 and 16 is provided, respectively, with inlet valves 18 and 118 and discharge valves 19 and 119 in-

the outer periphery of the opposite end portions of the associated cylinders 20 and 120. Both cylinders 20 and 120 define compression chambers 21 and 121 for the reciprocative pistons 22 and 122 for the low pressure stage 15 and the high pressure stage 16, respectively. The cylinders 20 and 120 are further provided with a water jacket 23 and 123, respectively, around the intermediate and at the end portions thereof.

Encircling the high pressure cylinder 120 is a housing 124 that cooperates with the cylinder 120 to form a chamber which is subdivided by outwardly extended support or rib members 125 and 126 that, respectively, encircle and extend longitudinally of the cylinder 120 to form clearance pockets 127 and inlet and outlet passages 128 and 129, respectively, for the compressor. In this respect the high and low stages are similar. Accordingly the low pressure stage 15 is provided with a housing 24 defining a chamber which is subdivided by ribs 25 and 26 forming clearance pockets 27 and inlet and outlet passages 28 and 29, respectively. In the low pressure stage an additional member 30 extends partially around the cylinder 20 and cooperates with the housing 24 and the member 23 to form a by-pass passage 31 that communicates the inlet 28 and outlet 29 of that stage.

In this instance there are two clearance pockets 27 and 127 positioned at each end of the associated cylinder, 20 or 120 which are communicated with the compression chambers 21 and 121, through ports 32 and 132, respectively. It is through these ports 32 and 132 that the flow of pressure fluid is controlled by the clearance valves 11 and 111 mounted in the housings 24 and 124, respectively. With this arrangement a step-by-step unloading of the compressor is available, and, in order to accomplish complete unloading, at least one clearance pocket 127 at each end of the housing 124 of the high pressure stage 16 is communicated with the inlet passage 128 thereof through the by-pass valve 14 mounted in the support member 126. This arrangement in cooperation with the passage 31, provides a flow path for reverse flow of fluid from the high pressure cylinder to the inlet side of the low pressure cylinder whenever the by-pass valve 14 and the clearance valve 111 associated therewith are both open.

Automatic control is maintained over the complete unloading of the high pressure stage 16 of the compressor through the means provided for controlling the communication between the clearance pockets 127 and the inlet 128, of the high

pressure stage 16, in response to variations in pressure in the inlet 128, or intercooler 17; and to this end, the fluid pressure operated valves 14 are designed to be actuated by the fluid, the flow of which they control and are mounted in the housing 124 in such a manner as to be exposed to the pressure differential between the clearance pockets 127 and the inlet 128. As shown, each of the valves 14 comprise a tubular member 33 having a recess 34 therein for the reception of the valve member 35. The member 35 is provided with heads 36 and 37 at the opposite ends thereof and the inner, with respect to the housing 124, head 36 resides in an enlarged portion 38 of the recess 34. The material forming the outer end of the enlarged portion 38 is tapered to form an annular seat 39 which cooperates with a complementary surface on the head 36. This seat area, or complementary surface, on the head 36 is exposed to pressure fluid in pocket 127 whenever the head 36 moves from its seat, thereby increasing the area of pressure surface exposed for actuating the valve member 35 into the open position, and snap action of the valve occurs.

Positioned, respectively, inwardly and outwardly of the seat 39 are holes 40 and 41 in the tubular member 3. With this construction communication between the holes 40 and 41 is controlled by the action of the valve member 35 which, in this instance, is actuated outwardly against the seat 39 to cut-off communication between the holes 40 and 41 by the action of fluid pressure on the inner end surfaces of the heads 36 and 37, and is actuated inwardly into the open position by fluid pressure on the outer surface of the head 36 and by means of a spring 42 interposed between the head 37 and the material forming the outer end of the recess 34. The outer end of the recess 34 is exposed to the atmosphere through a vent 43 in order to permit free movement of the member 35 in the recess. As best shown in Figure 3, the valves 14 are mounted in the support members 126 in such a manner that the outer holes 41 are exposed to the clearance pockets 127 and the inner holes 40 are exposed to the inlet 128 of the high pressure cylinder; thus the valves 14 serve as a means for controlling communication between the clearance pockets 127 and the inlet 128 in accordance to predetermined pressure variations existing in the inlet 128.

The valve 13 that cooperates with the valve 14 to completely unload the compressor, is mounted in the housing of the low pressure stage 15 and serves as a means for controlling the flow of air through the passage 31 that communicates the inlet and outlet of that stage by controlling the flow of fluid through an opening 44 in a member 45 positioned across the passage 31. As arranged, the valve 13 is held in the open position by means of a spring 46 and is biased in the closed position by the action of the pressure fluid delivered thereto through a conduit 47 connected in the regulating device 12. The valve 13 is, in this instance, actuated into the open position to completely unload the low pressure cylinder whenever the pressure in that part of the fluid system (not shown) in which the regulating device 12 is connected, reaches the predetermined value at which the regulator 12 exhausts the pressure fluid from the conduit 47. Subsequently the high pressure cylinder will be unloaded through the intercooler 17 in that the communication of the inlet 28 with the outlet 29 of the low pres-

sure stage necessarily causes the pressure to drop in the intercooler 17, which in turn causes a drop in pressure in the inlet 128 of the high pressure stage. The latter drop in pressure permits the spring 42 to bias the valve member 35 into the open position and thereby establish communication between the clearance pockets 127 of the high pressure stage and the outlet 29 of the low pressure stage.

The valves 11 and 111 may be of any conventional air operated type clearance valve. By way of illustration these valves may be similar in construction and operation to the valve 13. Accordingly whenever the regulator 12 exhausts pressure fluid from a clearance valve, the valve is unseated to communicate the associated clearance pocket with the compression chamber to partially unload the compressor. Conversely whenever the regulator valves fluid to the clearance valve, it is seated to cut off such communication and load the compressor.

Under normal operating conditions the by-pass valves 13 and 14 are held in the closed position and the regulator 12 controls the operation of the clearance valves 11 in the usual manner. In the event that the demand on the compressor is such that complete unloading of the compressor is desirable, the pressure fluid is exhausted from the regulator by either a manually operated or automatic means, not shown, and the regulator 12 will in turn exhaust pressure fluid from the by-pass valve 13 and the clearance valves 11 so that the pressure in the intercooler 17 immediately drops to a value at which the by-pass 14 is actuated into the open position and any fluid in a high or low pressure cylinder is exhausted to the inlet or suction side of the low pressure stage. On starting the compressor, pressure is built up in the fluid system and the regulator 12 closes the clearance control valves 11 and the low pressure by-pass valve 13 so that pressure is built up in the intercooler 17 to a point where the pressure on the surface of the inner end of the head 36, moves the valve member 35 inwardly against the pressure of the spring 42 and closes the valve 14. The compressor is now in condition to operate in the usual manner.

It is now obvious that the present invention provides a simple and effective means for completely and automatically unloading the high pressure stage of a compressor in cooperation with the unloading means for the initial, or low pressure, stage. This, in starting the compressor, reduces the starting torque on the prime mover, such as a synchronous motor, by relieving the pressure on the compressor piston; and prevents whipping of the piston and undue strain in the prime mover due to the compression and expansion of fluid trapped in the high and low pressure cylinders when the compressor is being shut down. The automatic feature of the high pressure by-pass valve 14 also eliminates any need for external piping and permits the valve 14 to be adapted wholly within the housing 124.

While I have shown and described a specific form of my invention it is to be understood that various changes and modifications may be made without departing from the spirit of the invention as set forth in the appended claims.

70 I claim:

1. The combination with a multi-stage compressor having a pair of cylinders connected in series and inlets and outlets and clearance pockets for the cylinders, of an unloader comprising means communicating the clearance

pockets and the inlet of one of the cylinders, pressure responsive means for controlling the communication between said clearance pockets and inlet, said means being actuated by pressure fluid in the inlet of the cylinder to which it is adapted, means for communicating the inlet with the outlet of the other cylinder, and means for controlling communication established by the last said means.

2. The combination with a multi-stage compressor having a plurality of cylinders with inlets and outlets and clearance pockets therefor, connecting means for communicating the inlet of one cylinder with the outlet of the cylinder of the preceding stage, comprising means for 15 communicating the clearance pockets with the inlet of the associated cylinder for all but the initial stage, means for controlling the last said communication, the last said means being responsive to pressure variation in the inlet of the 20 cylinder with which it is associated, means for communicating the inlet with the outlet of the initial stage, and means for controlling communication established by the last said means.

3. The combination of a multi-stage compressor having high and low pressure stages, cylinders for the high and low pressure stages having inlets and outlets for pressure fluid,

5   housings for said cylinders, clearance pockets for said cylinders, means for directly communicating the inlet and the clearance pockets of the high pressure stage, valve means within the housing for the high pressure stage for automatically controlling said communication between the clearance pockets and the inlet, said valve means acting responsively to the fluid pressure in the inlet of the high pressure stage, means for communicating the inlet with the outlet of the low pressure stage, valve means for controlling said communication for the low pressure stage, and means for controlling the operation of the last said valve means.
